SEARCHED AND SERIALIZED COPY
UNITED STATES PATENT OFFICE.

WILLIAM C. LAMPE, OF PITTSBURGH, PENNSYLVANIA.

DETACHABLE TOOTH-FACING FOR BRIDGE AND PLATE WORK.

1,070,494.

Specification of Letters Patent. Patented Aug. 19, 1913.

Application filed February 24, 1912. Serial No. 679,706.

To all whom it may concern:

Be it known that I, WILLIAM C. LAMPE, a resident of Pittsburgh, Allegheny county, State of Pennsylvania, have invented a new 5 and useful Improvement in Detachable Tooth-Facings for Bridge and Plate Work, of which the following is a full, clear, and exact description, reference being had to the accompanying drawings, forming part of 10 this specification, in which—

Figure 1 is a perspective view of a bridge of six teeth with two of the porcelain facings removed; Fig. 2 is a front view of one of the facings with the securing pin re- 15 moved; Fig. 3 is a section on the line III—III of Fig. 2; Fig. 4 is a front view of one of the backing plates; Fig. 5 is a detail view of one of the securing pins; Figs. 6 and 7 are sectional views illustrating the 20 application of my invention to different shapes of facings; Fig. 8 is a vertical section through one of the finished teeth of Fig. 1; and Figs. 9 and 10 are detail views showing different forms of the securing member.

25 My invention is designed to provide means of simple and convenient character for securing tooth facings of porcelain or similar material to a metal backing, and further, to provide means of this character, 30 whereby the tooth facing can be readily removed from the backing, should breakage or other causes render this necessary or desirable.

35 My invention consists particularly in a securing device or pin of novel form, and also in such pin in combination with a tooth facing particularly adapted for use therewith.

40 In the accompanying drawings, the numeral 2 wherever seen designates a porcelain facing, which is formed in the usual manner, but which is provided with two small pin holes 3 extending therein, one above the other, and having their outer end portions united by a shallow vertically extending groove 4.

45 5 designates the metallic backing plates for the porcelain facings, each of which is formed with an outwardly turned edge 6, to fit the corresponding portion of the facing, and thereby provide metal rims for the incisive edges of the teeth. Each facing is secured to its backing 5 by means of a specially formed pin having three prongs 55 7, 8 and 9. The two prongs 7 and 8 are adapted to fit into the perforations 3 in the

porcelain facing in the manner shown, while the third prong 9 extends through a small perforation 10 into the backing plate.

In fitting up a piece of bridge work, the 60 several teeth are fitted to their respective backings, the pins are inserted in the backings, and the porcelain facings are temporarily engaged therewith and the entire piece of work properly shaped up. The 65 porcelain facings are then removed, the prongs 9 of the securing pins are bent over against the back surfaces of the backing plates and are soldered thereto, or are embedded in the investment 10 formed of solder. The porcelain facings are then engaged with the prongs 7 and 8 of the pins and are firmly secured thereto by means of the usual cement.

The connecting portions of the pins be- 75 tween the prongs 7 and 8 lie within the shallow vertical grooves 4 of the facings, thereby preventing any tendency of the facings to rotate on the pins. If the facing becomes broken at any time in use, it can be 80 readily removed from the pins and a new facing applied without dismantling the entire bridge.

Fig. 9 shows a modified form of the se- 85 curing pin, in which the shank 9^a is split to form two prongs which, after insertion through the backing plate, can be bent over upon the plate in opposite direction, as shown in dotted lines in Fig. 9.

Fig. 10 shows another modification in 90 which the pin is provided with two separated prongs 9^b, for insertion through the backing plate.

95 My invention is applicable to bridge and plate work for both the upper and lower jaws and to teeth of various shapes and sizes. Thus, in Figs. 6 and 8, I show the invention applied to molar teeth.

I claim:

1. As a new article of manufacture, a se- 100 curing device for tooth facings, consisting of a pin having a transverse connecting portion with two substantially parallel prongs projecting therefrom in one direction to form an open U-shaped portion to engage a tooth facing, the inner sides of said prongs 105 being substantially at right angles to the connecting portion, and the connecting portion having a bendable prong projecting in the opposite direction; substantially as de- 110 scribed.

2. As a new article of manufacture, a se-

curing device for tooth facings, consisting of a pin having two substantially parallel separate prongs projecting in one direction to form an open U-shaped portion to engage a tooth facing, and having another prong projecting in the opposite direction from the connecting portion of the U, the last named prong being bendable, and also being split longitudinally whereby the two portions thereof may be bent in opposite directions, substantially as described.

3. The combination with a tooth member having a shallow surface groove in its back-
10 ing face, and a small aperture extending into

the member at each end of said groove, and 15 a backing plate, of a securing device comprising a pin having spaced prongs which enter said apertures, a portion connecting the prongs and which lies in the surface groove, and an oppositely projecting prong 20 which is bent over and down against the backing, substantially as described.

In testimony whereof, I have hereunto set my hand.

WILLIAM C. LAMPE.

Witnesses:

S. LEE McBRIDE,
FRANK McANENY.
